CLAIM

I claim the ornamental design for a bin, as shown and described.

DESCRIPTION

FIG. 1 is a front/right/top perspective view of a first embodiment of a bin (a front/left/bottom perspective view being a mirror image thereof);

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a front/right/top perspective view of a second embodiment of the bin (a front/left/bottom perspective view being a mirror image thereof); and

FIG. 9 is a rear/left/bottom perspective view thereof (a rear/right/bottom perspective view being a mirror image thereof).

FIG. 10 is a front/right/top perspective view of a third embodiment of the bin (a front/left/bottom perspective view being a mirror image thereof);

FIG. 11 is a left side elevational view thereof;

FIG. 12 is a right side elevational view thereof;

FIG. 13 is a front elevational view thereof;

FIG. 14 is a rear elevational view thereof;

FIG. 15 is a top plan view thereof; and

FIG. 16 is a bottom plan view thereof.

FIG. 17 is a front/right/top perspective view of a fourth embodiment of the bin (a front/left/bottom perspective view being a mirror image thereof);

FIG. 18 is a front elevational view thereof;

FIG. 19 is a rear elevational view thereof;

FIG. 20 is a left side elevational view thereof;

FIG. 21 is a right side elevational view thereof;

FIG. 22 is a top plan view thereof; and

FIG. 23 is a bottom plan view thereof.

FIG. 24 is a front/right/top perspective view of a fifth embodiment of the bin (a front/left/bottom perspective view being a mirror image thereof); and

(Continued)

FIG. 25 is a rear/left/bottom perspective view thereof (a rear/right/bottom perspective view being a mirror image thereof).

FIG. 26 is a front/right/top perspective view of a sixth embodiment of the bin (a front/left/bottom perspective view being a mirror image thereof);

FIG. 27 is a left side elevational view thereof;

FIG. 28 is a right side elevational view thereof;

FIG. 29 is a front elevational view thereof;

FIG. 30 is a rear elevational view thereof;

FIG. 31 is a top plan view thereof; and,

FIG. 32 is a bottom plan view thereof.

The broken lines show portions of the bin that form no part of the claimed design. The stippling in FIGS. 10-16 and 26-32 indicates that the claimed design is made of wholly or partially transparent (“clear”) or wholly or partially non-transparent material.
